UNITED STATES PATENT OFFICE.

JOHN A. SVENSON, OF PITTSBURGH, PENNSYLVANIA, ASSIGNOR OF ONE-HALF TO
JESSE J. SHUMAN, OF PITTSBURGH, PENNSYLVANIA.

MIXING-MACHINE.

1,239,537.

Specification of Letters Patent. Patented Sept. 11, 1917.

Application filed June 14, 1916. Serial No. 103,606.

To all whom it may concern:

Be it known that I, JOHN A. SVENSON, a citizen of the United States, residing at Pittsburgh, in the county of Allegheny and

5 State of Pennsylvania, have invented certain new and useful Improvements in Mixing-Machines, of which the following is a specification.

This invention relates to machines for 10 mixing various materials, as, for example, substances used in the production of concrete. The invention relates particularly to machines comprising a revoluble drum.

The mixing drum must have large unobstructed end-openings for the entry and exit of the treated materials. This requirement has led to the common practice of rotatably mounting the drum upon rollers which support the drum on heavy rings or bands encircling the periphery of the drum, since this method of drum support left the drum ends free. However, various practical difficulties arise out of this manner of supporting the drum. Abrasive materials soon collect on the 20 contact surfaces of the rollers and bands and cause rapid and unequal wear at these points. In addition to the actual destruction of the parts, such wear results also in a change of the center of rotation, which 25 fault is very detrimental, particularly when the drum is rotated by means of a pinion meshing with a toothed rim on the drum. The accuracy of this method of rotating the drum is destroyed as soon as the center of 30 rotation has been changed.

The object of this invention, generally stated, is to avoid these difficulties and still provide for the entry and exit of the materials through the ends of the drum.

40 In the accompanying drawings, Figure 1 is a vertical central sectional view through a mixing machine embodying the features of my invention. Fig. 2 is a fragmental detail view of the discharging means. Fig. 45 3 is an elevation of the left-hand end of the machine as shown in Fig. 1. Fig. 4 is a plan view of a bracket comprised in the construction. Fig. 5 is an inner end elevation of the bracket.

50 The supporting frame of the machine may be of any suitable character. Herein is shown a frame comprising two horizontal beams 1 and a pair of uprights 3 and 4 secured to said beams, respectively. Rigidly secured to the uprights 3 and 4 are two

horizontal inwardly-extending brackets 5. One of these brackets is shown in plan and in end view in Figs. 4 and 5. As there indicated, the bracket 5 is of U-form and comprises a pair of parallel arms 6 arranged to be secured at their outer ends to the uprights hereinbefore mentioned, the inner ends of said arms being joined by a transverse portion 7. Upon the transverse portion 7 is an inwardly extending socket or sleeve 8. The sockets 8 of the brackets 5 are axially alined and contain the ends of a stationary shaft 9. Said shaft is rigidly secured to the brackets 5 by means of screws 10 extending through the transverse portion 7 and into the ends of the shaft. The shaft 9 and screws 10 serve to secure the brackets 5 rigidly together and thus unite the uprights 3 and 4 and give stability to the framework.

Upon the shaft 9 is rotatably mounted a sleeve 11 extending from one bracket 5 to the other. To prevent gritty materials from reaching the contacting surfaces of the shaft 9 and sleeve 11, the ends 11^a of the sleeve 80 are extended to telescope with and contain the sockets 8 of the brackets 5, clearance being provided between the periphery of said sockets and the interior of the ends 11^a. I further provide upon each portion 7 a 85 shield 12 which overlies the adjacent sleeve-end 11^a. The shield 12 extends over the top of the sleeve-end 11^a and vertically along the sides of said sleeve-end, the lower side or end of the shield being open to permit 90 the escape of any gritty materials that may enter the shield through the space between the upper portion of the shield and the upper portion of the sleeve-end 11^a.

The drum 13 has end walls 13^a, each end wall having a central opening of ample size for the entrance and egress of the materials operated upon. The drum is rigidly secured to the sleeve 11 by means of a plurality of spokes or tie-rods 14, each secured at 100 one end to the sleeve 11 and at its opposite end to the peripheral wall of the drum. The form of these rods and their number and relative position may be other than as herein shown, but the illustrated construction 105 is preferred. It will be noted that the rods 14 extend in an inclined position and that adjacent rods are oppositely inclined. This staggered arrangement of the rods gives to the drum the requisite stability in opera- 110

tion. The rods may be inserted from the outside through openings 15 in the drum. The inner ends of the rods are threaded for insertion into screw-threaded openings in 5 the sleeve 11. The outer ends of the rods are secured to the drum by means of beveled washers 16 and nuts 17. The nuts 17 provide convenient means for accurately locating the sleeve 11 in the axis of the drum 13.

10 Any suitable means may be provided for charging the drum. Herein is shown a spout 18 secured to the uprights 4, the lower end of the drum extending within the central opening 19 in one end wall 13^a of the 15 drum 13.

Any preferred means may be provided within the drum 13 to assist in mixing the materials to be treated and to advance and elevate said materials. Herein I have 20 shown an annular series of spirally-placed blades 20 secured to the inner periphery of the drum 13 in position to elevate and advance the materials entering through the spout 18. There is also shown an annular 25 series of buckets 21 fixed to the inner periphery of the drum in position to elevate the materials advanced by the blades 20. 22 is a plate secured to the transverse portion 7 of the bracket 5 which is located 30 at the discharge end of the drum, said plate being inclined downwardly toward the charging end of the drum. As shown in Fig. 1, the plate 22 is located in the plane of the orbit of the buckets 21 and within 35 said orbit. Materials falling on said plate are directed out of the orbit of the buckets and toward the charging end of the drum.

While any suitable means may be employed to discharge the mixed materials, the 40 means preferably employed comprises a chute 23 fixed to the uprights 3 and extending through a central opening 24 in the adjacent end of the drum. The chute 23 occupies an inclined position, its upper inner 45 end being sufficiently far within the drum so that materials discharged from the ascending buckets 21 will be received in the chute. The chute is provided at its upper end with a movable bottom section 25 which 50 is fixed to an arm 26 attached to a rock-shaft 27, said rock-shaft being journaled in the side walls of the chute 23. To the lower side of the bottom 25 is pivoted a link 28 which serves to connect said bottom with a 55 crank arm 29 fixed upon a rock-shaft 30. Said shaft is mounted in the uprights 3 and is provided with an operating crank 31. During the mixing of the materials the bottom 25 occupies the position shown in 60 dotted lines in Fig. 1. The materials spilled from the buckets 21 strike the bottom 25 and slide onto the plate 22; the latter deflects the materials toward the charging end of the drum, where they undergo further 65 agitation.

When the mixture has been retained in the drum for the desired length of time, the operator swings the crank 31 into the position shown in full lines in Fig. 1, thus placing the bottom 25 in position to direct the 70 mixed materials discharged by the ascending bucket 21, out through the chute 23.

The means for lubricating the bearing for the sleeve 11 comprises an oil cup 32 supported upon a tube 33 extending through 75 the charging spout 18 and communicating with a chamber 34 in the central portion of the part 7 of the bracket 5 connected to the uprights 4. In the adjacent end of the shaft 9 is an oil duct 35 communicating with the chamber 34 and with the lower surface of the shaft 9 at 36.

Any suitable form of drum-rotating means may be employed. Herein is shown a toothed ring 37 fixed upon the periphery 85 of the drum and arranged to mesh with a driving pinion (not shown).

It will be seen that the drum 13 is supported at its axis rather than at its periphery, and that this has been accomplished 90 without materially obstructing the charging and discharging openings in the ends of the drum. The bearings that support the drum are effectively protected against the entrance of grit and thus are protected against excessive wear, besides insuring permanence in the relation of the center of rotation to the driving pinion.

It will be noted that the brackets 5 are alike in size and form, which feature contributes to economy in construction.

I claim as my invention:

1. A batch mixing machine having, in combination, a supporting framework, a stationary U-shape bracket, the ends of the 105 arms of which are rigidly fixed to said framework, a shaft fixed at one end to the closed end of said bracket, means attached to the supporting framework for supporting the other end of the shaft, a mixing drum having end walls to retain the material therein, each end wall having a central opening, said bracket extending through the opening in one end wall of the drum, the closed end of the bracket being within the 115 drum, means for rotatably supporting the drum on said shaft, and an inlet spout 120 stationarily located in position to project into the opening in the last mentioned end wall of the drum and discharge material through the space between the arms of said bracket.

2. A batch mixing machine having, in combination, a supporting framework, two stationary brackets rigidly fixed to said framework, said brackets extending toward each other, a mixing drum having end walls to retain the material therein, each end wall having a central opening, said brackets extending through the openings in the end walls of the drum, the inner ends of the 130

- brackets being within the drum, means connected to the drum and supported by the inner ends of said brackets for rotatably supporting the drum, means for charging 5 material into the drum through the central opening in one end wall of the drum, and means for discharging material through the central opening in the other end wall of the drum.
- 10 3. A batch mixing machine having, in combination, a supporting framework, a stationary U-shaped bracket rigidly fixed to said framework, a mixing drum having end walls to retain the material therein each end 15 wall having a central opening, said bracket extending through the opening in one of the end walls of the drum, the closed ends of the bracket being within the drum, a support fixed to the framework opposite said 20 bracket, means connected to the drum and supported by the inner end of said bracket and by said support for rotatably supporting the drum, a discharge chute extending through the central opening of one end wall 25 of the drum and extending from a point within the drum to a point outside the drum, said chute extending through the space be-

tween the arms of the U-shaped bracket, and elevating devices within the drum for discharging material onto said chute.

4. A mixing machine having, in combination, a rotatably mounted drum having end walls, one end wall having a central charging opening and the other end wall having a central discharging opening, elevating buckets attached to the inner side of the peripheral wall of the drum near the discharging end of the drum, means located within the orbit of the buckets and in the plane of the buckets for directing materials falling upon it out of the orbit of the buckets toward the charging end of the drum, a discharge chute extending through the discharging opening, said chute including a member movable into and out of position to intercept materials which otherwise would fall upon said directing means, and an inclined member stationarily located within the drum and below the movable chute member for directing falling materials toward the charging end of the drum.

In testimony whereof, I have hereunto set my hand.

JOHN A. SVENSON.
